ATTORNEY.

UNITED STATES PATENT OFFICE.

GUSTAF A. OBERG, OF OAKLAND, CALIFORNIA.

CARRIER FOR PENCILS.

No. 888,842.

Specification of Letters Patent.

Patented May 26, 1908.

Application filed May 28, 1907. Serial No. 376,072.

To all whom it may concern:

Be it known that I, GUSTAF A. OBERG, a citizen of the United States, residing at Oakland, in the county of Alameda and State 5 of California, have invented new and useful Improvements in Carriers for Pencils and the Like, of which the following is a specification.

The object of the present invention is to provide a simple and inexpensive device to 10 be attached to a hat for the purpose of holding a pencil or other small article.

It is especially adapted for use by expressmen, draymen, shipping clerks, and other persons occupied out of doors, whose 15 business requires frequent use of a pencil.

In the accompanying drawing, Figure 1 is a side view showing the device attached to a hat; Fig. 2 is an enlarged perspective view of the device detached; Fig. 3 is a cross 20 section.

Referring to the drawing, 1 indicates the entire device which is formed of a piece of wire bent as follows:—At one end it is formed into a pin, shown at 2, having a sharpened 25 point 3, the end of said pin being bent in a loop 4 and then extending in a reverse direction as shown at 5, but having two loops 6 formed therein, then bent at right angles as shown at 7, and then back on itself, as shown 30 at 8, and having two loops 9 therein, then bent at right angles and passing through the loop 4, and then bent back at right angles, as shown at 10 and having loops 11 formed therein, and then bent around the part 7, 35 and into a hook or guard 12 adapted to engage the point of the pin. The loops 6 extend straight out or at right angles to the surface passing through the parts 5, 8 and 10, but the loops 9 and 11 at the sides lie in

curved surfaces of a general ogee form, that 40 is to say, they extend first outwards and then inwards and then outwards again at the top. They thus form spring clips adapted to retain the pencil in position while the outer swell or bend permits of the pencil 45 being readily inserted. The pin, being movable about an axis transverse to the direction of the loops, can readily be inserted in the hat band so that the loops then extend at the proper position to engage and 50 retain a pencil. The device can also be used to carry other small articles, as a match box.

I claim:—

1. A device of the character described, comprising a piece of wire bent to form members 55 bent into loops extending substantially at right angles to the surface through said members, a pin movable about an axis transverse to said direction of said loops, and a guard engaging the point of the pin, substantially as described.

2. A device of the character described comprising a single piece of wire bent to form a central member and two side members, all of said members being bent into 65 loops extending substantially at right angles to the surface through said members, and adapted to engage the sides of a pencil or the like, and also formed into a pin and a guard to engage the point of the pin, substantially as described.

In testimony whereof I have hereunto set my hand in the presence of two subscribing witnesses.

GUSTAF A. OBERG.
